ATTORNEY.

UNITED STATES PATENT OFFICE.

OSCAR HOCHBERG, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

CAR END FRAMING.

1,140,680.

Specification of Letters Patent. Patented May 25, 1915.

Application filed June 17, 1912. Serial No. 704,255.

To all whom it may concern:

Be it known that I, OSCAR HOCHBERG, residing at St. Louis, Missouri, and being a citizen of the United States, have invented 5 certain new and useful Improvements in Car End Framing, of which the following is a full, clear, and exact description, such as will enable others skilled in the art to which it appertains to make and to use the 10 same, reference being had to the accompanying drawings, which illustrate the preferred form of the invention, though it is to be understood that the invention is not limited to the exact details of construction 15 shown and described, as it is obvious that various modifications thereof will occur to persons skilled in the art.

The object of the invention is to provide 20 an end framing capable of withstanding the severe wrenching to which car frames are subjected in service, especially the end frames of cars wherein provision must be made for doorways for the passage of freight or passengers.

25 The problem of properly bracing the ends of cars is not so great in cases where the required opening is not larger than that usually found in passenger cars, but where freight of great bulk such as automobiles or 30 other vehicles, machinery and the like are to be carried, door openings as large as the car end will permit are necessary, in which case the problem of bracing the car end becomes important.

35 It is the province of this invention to provide an end framing suitable not only for the purpose of resisting stresses induced by the surging and swaying of the car body, but also to the requirements of the particular 40 type of car in which it is desired to employ the invention.

Another and important object of this invention is to provide in the end frame organization, an upright member made up of 45 complementary sections having the same general configuration and secured together, each of said sections being provided on one edge

thereof with a stepped portion adapted to receive parts entering into the construction of the car. This arrangement enables the 50 builder to form the column with a minimum expenditure of time and labor in assembling the parts with the consequent reduction in the cost of the completed structure.

As shown in the drawings, the outer section of the column is arranged with its stepped edge farthest from the car side thus providing a pocket and jamb for the door, while the inner section is reversed and placed with its stepped edge in a position 60 to receive the corner nailing post securing the sheathing and lining of the car-wall together.

It will be observed that the stepped portion of one section is secured to the body 65 of the other, so that when assembled a stepped column of substantially box-section is obtained.

In the drawings, Figure 1 shows the invention applied to an automobile car end 70 with the doors arranged within the framing. The view at the left-hand side of Fig. 2 shows a horizontal section taken on line 2-2 of Fig. 1 through the wooden end plate with enough of its end broken away to show 75 the manner of connecting the upper end of the upright to the door lintel. The view at the right-hand side of the same figure is a section taken horizontally on line 2^a-2^a of Fig. 1 through the upright at a point above 80 the end sill showing the connection of the lower end of the upright to the end sill. Fig. 3 is a vertical section through one of the uprights taken on line 3-3 of Fig. 1, showing both top and bottom connections to 85 lintel and end sill respectively. Fig. 4 is a section taken on the line A-B of Fig. 2 showing the manner of connecting the upright, lintel, and side plate together on the inside of the car. Fig. 5 is a section taken 90 on the line C-D of Fig. 2 showing the connection of the upright to the side and end sills on the inside of the car. Fig. 6 is an isometric view of the upper corner arrange-

ment showing the inside corner band connecting the side and end plates together. Fig. 7 is an isometric view of a corner of the car showing a section through each of the 5 end sill, upright and side sill parts of the framing. Fig. 8 is an isometric view on an enlarged scale of the upper end of an upright coped out for the accommodation of the door lintel. Fig. 9 is an isometric view 10 showing in detail the manner of coping out the upper ends of the upright sections. Fig. 10 is an isometric view of an end of one of the side plates E. Fig. 11 is a vertical section 15 through the door lintel taken on line 11—11 of Fig. 13 at a point a little to one side of one of the uprights and its connections. Fig. 12 is a vertical section through the door lintel and the upper portion of one 20 of the uprights taken on line 12—12 of Fig. 11 showing the manner of connecting these parts. Fig. 13 is a plan of the side plate, 25 door lintel, and upright connection.

In several figures of the drawing, A indicates a car with its end constructed in accordance with the invention; B and C are the doors fitted within the framing; D indicates the end sill; E the side plate; F the side sill; G and H refer to the lining and sheathing respectively of the car wall; and 30 J indicates the uprights peculiar to the invention.

Of the sections making up the upright J, section 1 thereof forms the outside or sheathing of the end wall of the car and section 2 35 the inside or lining of said wall. These sections are made up of plates having a plurality of angular bends a—b along one edge thereof to form, in the outer wall section 1 of the column J, a pocket and jamb for the door and, in the inner wall section 2 of the 40 upright, a pocket for the rearwardly extending nailing post 3 for securing the lining G and sheathing H of the car side. Carriage bolts 4 and 5 secure the nailing posts 3 which are of wood or other fibrous material 45 to the portion 6 of section 2 of the upright. Additional bolts 7 pass through the body of the section 1 and flanged portion 8 of section 2 and serve to further secure nailing post 3 to upright J. Flange 6 extending 50 rearwardly from the body of section 1 serves as a pocket for the doors B or C and gives sufficient space for the accommodation of jamb strip 9 attached to flange 8 of section 1 and body of section 2.

The doors swing on hinges 10 mounted on the body of section 1 of the uprights J and when closed occupy a position within and close the opening bounded by the end sill, D, 60 the elbowed portion 6 of the outer section 1 of the uprights, and the end plate K.

The end sill D comprises the Z-bar 11, the reinforcing angle 12 arranged with its hori-

zontal flange 12^a flush with the top of flange 11^a of the Z-bar, and the cover plate 13 connecting Z-bar 11 and reinforcing angle 12. The end sill D, is preferably of constant cross section and extends from one side of the car to the other and is connected to the side sills F by means of gussets 14 and the 70 ends of the cover plate 13 which members or plates 13 and 14 respectfully overlap and underlap the top and bottom flanges of the Z-shaped side sills and are riveted thereto. The cover plate 13 between the uprights J 75 is flanged as at 13^a, Fig. 7, to provide securing means for the threshold piece 15, but at the uprights the cover plate is flat as at 13^b to accommodate connecting pieces 16 preferably of angle shape securing the inner bottom portion of the uprights J to the end sill D. Angle pieces 17 connect the lower outer ends of the uprights to the end sill D.

As shown in Fig. 8, the upper portions of the uprights are coped out for the reception 85 of the end plate member K of substantially Z section arranged to lie between the upper ends of the upright sections 1 and 2. The flanges 6 and 8 of the section 2 are cut away substantially in the plane of the horizontal 90 web of the end plate Z-bar K but the body portion 2^a of the section extends above the web of said Z-bar end plate for connection to the angle piece 18 secured to the web of the Z-bar. The flanges 6 and 8 of section 1 95 of the upright also terminate in the plane with those of section 2, while the body plate 1^a of the section continues upwardly for connection with the upstanding flange 19 of the Z-bar end plate K. It will be observed that 100 the flanges 6 of the sections are coped out as at 1^b and 2^b to receive the depending flange 20 of the end plate K. It will be noted that flange 8 of section 1 lies in a plane on the 105 outside of the depending flange 20; this is 105 done to permit the riveting of that part to the depending flange of the Z-bar end plate.

The vertical flange 22 of the side plate angle E is cut away at the upright to clear 110 extension 2^a of the upright section 2 and the upstanding flange 18^a of connection 18; inside corner band 21 connects the side plate and the end plate, the upper corner connection is further reinforced by the outside corner band 23 connecting both side and end 115 plates.

There is one advantage in the peculiar construction of the uprights and that is that the work entering into their construction may be done in the shops and machine riveted after which the complete member may be taken to the work on the track and assembled with the rest of the car frame members.

It will thus be seen that there has been 125 produced a sectional upright having recesses in its opposite faces, and these recessed por-

tions of the upright are formed by a plurality of angular bends in each of the sections making up the post or upright.

What I claim and desire to secure by Letters Patent is:

1. A car end framing comprising an end plate, an end sill, and stepped uprights, each of said uprights being made up of a plurality of similar sections provided with seats for the end plate. 10
2. A car end framing comprising an end plate, an end sill, and stepped uprights, each of said uprights being made up of a plurality of sections having the same general configuration and coped at their upper ends to provide seats for the end plate. 15
3. A car end framing comprising an end plate, an end sill, and hollow stepped uprights, each of said uprights being made up of a plurality of similar sections coped to receive the end plate. 20
4. A car end framing comprising an end plate, an end sill, and a pair of hollow stepped uprights, each of said uprights being made up of a plurality of sections having the same general configuration and coped to receive portions of the end plate, said coped sections combining to provide a seat for said end plate. 25
5. A car end framing comprising an end plate, an end sill, and a pair of hollow stepped uprights of box or rectangular section, each of said uprights being made up of a plurality of similar sections coped to receive the end plate and combining to provide a seat therefor. 30
6. A car end framing comprising an end plate, an end sill, and a pair of hollow stepped uprights of box or rectangular section, each of said uprights being made up of a plurality of sections having the same general configuration and combining to provide a seat for the end plate. 40
7. A car end framing comprising an end plate, an end sill, and stepped uprights, each of said uprights being made up of a plurality of matched sections of the same general configuration and coped to receive the end plate and to provide a seat therefor. 45
8. A car end framing comprising an end plate, an end sill, and hollow stepped uprights, each of said uprights being made up of sections having the same general configuration, said sections being reversely arranged with respect to each other and coped to provide a seat for the end plate. 50
9. An end construction for a car comprising in combination an end sill, an end plate, a vertical body post having spaced extensions lapping said end plate and connection member resting on said end plate and secured directly to said lapping extensions of the post. 60
10. An end construction for cars comprising in combination an end sill, an end plate, a car post coped at its upper end to receive the end plate and comprising a couple of similarly formed members, said members having each a web portion and a stepped flange portion, the stepped flange portion of one member being secured directly to the web portion of its companion member, said web portions extending beyond the stepped flanged portions for attachment to the end plate. 65
11. A car body end framing comprising a pair of corner posts formed with recesses at their outer sides, nailing posts within said recesses and said posts forming at their upper ends recesses for an end plate and an end plate substantially within said recesses. 70
12. A car, a body end framing comprising posts formed of coupled complemental plates with oppositely stepped flanges secured to said complemental plates and forming at two sides recesses for fibrous inserts, fibrous inserts in said recesses and an inner lining secured to one of said inserts. 75
13. A car, a body end framing comprising posts formed of coupled complemental plates with oppositely stepped flanges secured to said complemental plates and forming at two sides recesses for fibrous inserts, fibrous inserts in said recesses and an outer lining secured to one of said inserts. 80
14. A car, a body end framing comprising posts formed of coupled complemental plates with oppositely stepped flanges secured to said complemental plates and forming at two sides recesses for fibrous inserts, fibrous inserts in said recesses and linings secured to one of said inserts. 85
15. In a car, corner posts comprising coupled complemental sections interlocking with and lapping an end plate, an end plate and an end sill connected with said posts. 90
16. In a car, an end plate, corner posts comprising coupled complemental sections provided each with a web portion and a flanged portion, the web portion of each of said sections extending upwardly beyond their respective flanged portions and lapping the end plates, said flanged portions being coped to provide a seat for the end plate. 95
17. An end construction for cars comprising an end sill provided with a cover plate having a flanged intermediate and flat end portions and posts supported upon the flat end portions of said cover plate and secured thereto. 110
18. An end construction for cars comprising an end sill provided with a cover plate having a flanged intermediate and flat end portions, posts supported upon the flat end portions of the cover plate and a threshold 125

piece arranged along the flanged portion of the cover plate and extending between said posts.

19. An end construction for cars comprising an end sill, posts rising from the end sill and provided each with an outer recess for the accommodation of a nailing post, and an inner recess providing a door jamb and jamb strip securing means.

10 20. An end construction for cars comprising an end sill, posts rising from the end sill

and having extensions lapping and interlocking with an end plate, an end plate seated between the extensions, a side plate resting upon the end plate, and connections uniting said parts. 15

In witness whereof I have hereunto set my hand in the presence of two witnesses.

OSCAR HOCHBERG.
